PATENTED

SEP 14 1869

Elisha S. Heath

Thomas G. Wilson
Wm. C. & F. Stone

United States Patent Office.

ELISHA S. HEATH, OF BALTIMORE, MARYLAND.

Design No. 3,659, dated September 14, 1869.

DESIGN FOR A FIRE-PLACE HEATER.

The Schedule referred to in these Letters Patent and making part of the same.

To all whom it may concern:

Be it known that I, ELISHA S. HEATH, of the city of Baltimore, and State of Maryland, have produced a new and original Design of a Self-Feeding Fire-Place Stove; and I hereby declare that the following is a full and exact description of the same.

A lower cylinder, made of cast-iron, ornamented with double Gothic windows, of German and French style—an improvement of design patented December 1, 1863.

An upper cylinder, surmounted with a cast-iron ornamental plate—helmet-shaped. This plate is attached to the front side of the upper cylinder, and contains a door, inserted for supplying coal, which is represented on photograph by letter C, and extending to letter D.

Attached to this upper cylinder is a cast-iron hopper or tube, extending from the line of this helmet-plate to within two inches of line of fire-bricks.

This hopper or tube is supported by the back line of fire-bricks, which is made, on its back part, of elongated shape.

I claim the ornamental figures and forms represented in and by the accompanying drawing or photograph, the whole forming an ornamental design for a self-feeding fire-place stove.

ELISHA S. HEATH.
